UNITED STATES PATENT OFFICE.

ARTHUR R. NOYES, OF OAKLAND, CALIFORNIA.

LINOTYPE-MACHINE.

No. 833,479.

Specification of Letters Patent.

Patented Oct. 16, 1906.

Application filed March 20, 1906. Serial No. 306,884.

To all whom it may concern:

Be it known that I, ARTHUR R. NOYES, a citizen of the United States, residing at Oakland, in the county of Alameda and State of California, have invented new and useful Improvements in Linotype-Machines, of which the following is a specification.

My invention relates to improvements in linotype and kindred machines in which a linotype or printing-slug is cast in a slotted mold against a line of matrices temporarily assembled against the face of the mold.

It consists in a mechanism by which the length of the slot in the mold may be changed to produce any desired length of slug without essential change or substitution of other parts.

It also comprises a combination of mechanism and details of construction, which will be more fully explained by reference to the accompanying drawings, in which—

Figures 1, 2, and 3 are sections in perspective showing the mold and liners. Figs. 4 and 5 are perspective views showing the movable jaw and the liner-actuating plate. Fig. 6 is a transverse section of the wheel and mold in position to eject. Fig. 7 is a transverse section of the wheel and mold in casting position with relation to a matrix. Fig. 8 is a perspective showing the jaws in their relative position. Fig. 9 is a detail of the arm 14 and shaft 15.

In this class of machines it is necessary to frequently change the measure or length of the linotypes or slugs in accordance with the width of the page or column of print required. This change is usually effected by removing a liner or distance-piece and substituting another of different length or by employing a liner which is slideable longitudinally within the slot.

By my invention I provide a series of transversely-movable liners and mechanism by which they are automatically actuated to close that portion of the slot not occupied by the linotype or slug while said slug is being cast and subsequently removing the liners, so as to leave the entire length of the slot free, thus allowing a single ejector-blade to be employed for any length of slug within the limit of the apparatus.

I have here shown only such portions of the well-known form of linotype-machine as will illustrate my improvements, and it will be understood that the remaining parts may

be constructed and arranged as known in any of the improved forms of this class of apparatus.

A is the intermittently-rotated wheel or disk, which carries the slotted mold 2. This mold is of the ordinary character fixed rigidly to the wheel and having its slot or mold proper normally opened at the front and rear side, so that it may coöperate with the line of matrices 3^a at the front, and with the mouth of the metal-pot at the rear.

The slot or cell 3 in which the slug is cast is of a length dependent upon the size and character of the machine, and within this slot the various lengths of slugs within its capacity are cast in the usual manner. The varying sizes of type, as agate and pica, may be compensated for by pieces 2^a of different thickness. In order to close such portions of the slot as are not to be occupied by the linotype or slug which is adapted to the particular measure or length of line being cast, I employ a series of independent liners, (well shown at 4.) Each of these liners 4 has a projection 5 upon its front edge. This projection is here shown, Fig. 2, as having its under surface inclined at an angle of about forty-five degrees. The incline or bevel upon coming in contact with the bar or plate 9, attached to the movable jaw 8, as the mold-carrying wheel is advanced horizontally toward the vise-frame forces the liners 5 to the top of the mold-slot. Each of these liners 4 has a notch or groove 5^a in its lower front edge.

The object of this notch is to provide a means of slightly raising and subsequently locking the liners which have not been raised by the plate 9. The upper edge of each of these liners 4 presents a perfectly smooth flat surface. The combination of these flat surfaces form the floor or bottom of the mold-slot 3, and to prevent the metal from running between the liners forming the bottom of the mold I have provided the threaded shaft 15, the operation of which will be hereinafter explained. These liners are guided and slideable below the slot 3 and are movable upwardly when the mold is in the casting position, so that they fill that portion of the slot which is not to be used. The matrices 3^a are assembled in the vise-frame or holder 6 between a fixed jaw (not shown) and a movable jaw, the movable jaw being adjusted to the length of slug required, and the matrices are locked in this vise-frame or holder.

Attached to the movable jaw 8 is a bar or plate 9. This plate extends the entire length of the movable jaw and is hinged at the rear and held flat against the bottom of the movable jaw by springs 9^a, so that its front edge projects in line with the beveled edges of the projections 5. The purpose of the hinge and spring is to relieve the pressure when the liners 4 have reached the top of the mold-slot and can move no higher. Provision is thereby made for different thicknesses of linotype-slug, as nonpareil, brevier, &c.

When the mold-carrying wheel A has been turned to the position in which the mold is substantially horizontal and in the plane of the matrices which have been assembled in the vise-frame, the wheel is advanced toward the vise-frame until the mouth of the mold 3 is in contact with the matrices which form the line of type to be cast. This movement brings the beveled or inclined edges 5 of the liners 4 into contact with the edges of the plate 9, and all of these liners exterior to the fine of matrices are thus forced upwardly and transversely across the mold-opening, thus closing it, so that no metal can enter the mold except at the point where the matrices are assembled. The retraction of the mold-wheel from the vise-frame retracts the liners from the plate 9, and they are thus free either to drop by gravitation or by direct force applied, as will be hereinafter described, thus leaving the full length of the mold open, so that the single ejector-blade which operates to force the linotype from the mold can be used for any length of line within the capacity of the mold, and no change in the ejector-blade need ever be made.

In order to insure the easy removal of the linotype from the mold, it is customary to make the mold slightly wider at the discharge side, so that the slug can be easily forced out by the ejector. In my construction the opposing sides of the mold are absolutely parallel, and in order to free the slug after casting I have shown a device by which the surface of the liners which form the bottom of the mold are slightly approached to the upper surface of the slot at the instant of casting and are retracted from the upper fixed side of the mold after the casting is completed. This device consists of a bar 10, mounted upon a shaft 11 and having its upper surface or edge formed as shown at 12, so that it will engage the lower correspondingly-inclined notched ends 5^a of the liners 4.

13 is an arm fixed to the end of the shaft 11 in such a manner that when the mold-wheel is advanced and the mold brought into position for casting this projecting arm 13 will contact with a projecting stud attached to the fixed jaw of the vise-frame and being thus pushed back will slightly rotate the shaft 11, this rotation acting to correspond-

ingly move the part 10, and thus acting against the notch in the lower edge of liners will operate to slightly raise and lock them and narrow the mold before the casting is made. As soon as the mold-wheel is retracted the pressure upon the arm 13 and arm 14 is relieved, and the liners are free to drop to their first position by gravitation, expansion of the slug, or by direct force applied as will be hereinafter described, thus insuring the easy removal of the slug. It is desirable to firmly compress these independent liner-sections together after they have been raised to fill that portion of the mold not necessary for the slug, and in order to do this I have shown an arm 14 mounted upon a screw-threaded shaft 15 at the end of the mold opposite from the arm 13. This arm 14 projects slightly in front of the face of the mold, and when it comes in contact with the vise-frame it is moved backwardly as the mold arrives in position for casting. This slight movement turns the screw-shaft 15 and advances it against the liners, which have been already raised to form the mold, and thus presses them together, so that the spaces between them will be absolutely closed and no metal will be allowed to enter. The retraction of the mold relieves the pressure upon this arm 14 and allows it to resume its normal position and free the liners, which, as previously stated, may drop by gravitation; but if they do not thus drop I have shown a device by which I insure their being lowered when pressure on the arm 13 is removed to free the mold for the operation of the ejector. This consists of an inclined or beveled projection 16, which stands parallel with the position of the mold when the wheel has been turned so that the mold stands in position to allow the ejector to act. This inclined surface is just at one side of the knife or planer by which the slug is trimmed as it is ejected, and when the mold is again advanced so that the ejector may act upon the slug this inclined surface 16 will contact with the projections of the liners the entire length of the mold, forcing each and all the liners to their extreme lower position, thus leaving the slug loose in the mold and allowing the passage of the ejector-blade.

From this construction it will be seen that the floor of that portion of the mold in which the slug is to be cast is practically composed of a series of transversely-arranged plates which are slightly raised to narrow that portion of the mold at the instant of casting and retracted after the cast is complete to allow the slug to be freely ejected, that the remainder of the liners are advanced so as to entirely fill that portion of the mold not occupied by the slug and before the latter is cast, and that by reason of this independent series of thin plates any desired length of slug can be cast within the limits of the mold. The

movable jaw 8, to which the bar or plate 9 is attached, is the only part to be adjusted in order to change the length of the slug or line, and such adjustment is already provided on 5 machines of this class.

I have here described a form of mechanism by which the desired movements may be conveniently effected and without material change in the machines as usually constructed, and it will be manifest that various modifications of the actuating mechanism may be effected without materially altering the character of my invention.

Having thus described my invention, what 15 I claim, and desire to secure by Letters Patent, is—

1. In a linotype-machine, a slotted mold and a series of transversely and mechanically operated slideable liner-plates by which the 20 working length of the mold is determined.

2. In a linotype-machine, a slotted mold, a series of transversely-disposed plates forming one side of the mold means by which any 25 number of said plates may be advanced to close the mold, and determine the length of the slug to be cast.

3. In a linotype-machine, a slotted mold, a series of transversely-disposed plates having inclined edges upon one side, a fixed plate 30 against which said inclines contact when the mold is advanced for casting whereby the transverse plates are advanced to fill the mold.

4. In a linotype-machine, a slotted mold, a 35 matrix-holding vise-frame toward which the mold is advanced, means for determining the length of the slug to be cast, said means consisting of plates, the upper edges of which normally form the bottom of the mold, a bar 40 carried by the vise-frame and adjustable to the length of the slug to be cast, inclined or cam edges formed upon the transverse plates, and contacting with said bar when the mold is advanced, whereby a sufficient number of 45 plates is advanced to fill all that portion of the mold, except that which is to be occupied by the slug.

5. In a linotype-machine, a slotted mold, a series of transverse plates forming the bottom 50 of the mold, mechanism by which a portion of said plates is advanced to determine the length of the slug to be cast, mechanism by which the remainder of the plates is slightly advanced to narrow the mold at the 55 instant of casting, and to retract said plates after the slug is cast.

6. In a linotype-machine, a slotted mold, a series of plates, mechanism by which a portion of said plates is advanced to close the 60 mold and determine the length of the slug to be cast, mechanism by which said plates are subsequently closed tightly together to form a solid filling for that portion of the mold.

7. In a linotype-machine, a mold having a 65 fixed and a movable side said movable side

composed of independently-movable sections, and means for advancing and retracting the movable sections to vary the length of the line.

8. In a linotype-machine, a mold having a 70 fixed side and an opposing side composed of independently-movable sections.

9. In a linotype-machine, a mold composed of a rigid portion including a fixed side, thin plates standing transversely across the 75 mold and forming its opposite side, and mechanism whereby a determined number of said plates may be advanced to close a portion of the mold, and limit the length of the 80 slug.

10. In a linotype-machine, a rigid portion including a fixed side of the mold, thin transverse plates, the edges of which form the opposite side of the mold, means adjustable with relation to the mold whereby a number 85 of said plates may be advanced to fill a portion of the mold and limit the length of the casting-chamber.

11. In a linotype-machine, a rigid portion including a fixed side of the mold, thin transverse plates, the edges of which form the opposite side of the mold, means adjustable with relation to the mold whereby a number 90 of said plates may be advanced to fill a portion of the mold and limit the casting-chamber, and means for subsequently compressing said plates in the direction of the length of the mold.

12. In a linotype-machine, a rigid mold including a fixed side, thin transverse plates, the edges of which form the opposite side of the mold, means adjustable with relation to the mold whereby said plates may be advanced to fill the mold, and temporarily 100 limit the length of the casting-chamber, and means by which the plates may be subsequently retracted to expose the full length of 105 said chamber for the passage of an ejector-plate.

13. In a linotype-machine, a rigid mold, including a fixed side, thin transverse plates, the edges of which normally form the opposite side of the mold, means by which a portion of said plates may be advanced to fill the mold, and limit the casting-chamber, means 110 by which those plates forming the bottom of said chamber may be advanced to slightly narrow the chamber before a slug is cast, and subsequently retracted to free the slug.

14. In a linotype-machine, a mold having 115 a fixed, and a sectional movable side, and means by which sections of said movable side may be advanced to determine the length of the casting-chamber, said means including beveled surfaces upon the sections, and an 120 adjustable opposing plate against which the surfaces are held in contact at the instant of casting.

15. In a linotype-machine, a mold having 125 a fixed and a sectional movable side, means

1 by which sections of the movable side may be advanced to determine the length of the casting-chamber, and means by which the sections are positively retracted, said means including inclined contacts carried by the sections, and fixed contacts against which the inclines are caused to impinge.

16. In a linotype-machine, a mold having a fixed and a sectional movable side, means 10 by which the section of the movable side may be advanced to determine the length of the casting-chamber, and means by which the sections are compressed together, after being positioned, said means including a pressure device, and means by which it is actuated before the cast is made.

17. In a linotype-machine, a mold having a fixed and a sectional movable side, means by which sections may be advanced to determine the length of the casting-chamber, and 20 other sections advanced to slightly narrow the mold, and surfaces of contact by which the sections are retracted to free the slug after casting.

In testimony whereof I have hereunto set 25 my hand in presence of two subscribing witnesses.

ARTHUR R. NOYES.
